SUPERIMPOSED CODED SIGNALING SYSTEMS

William L. McNabb, Turtle Creek, Pa., assignor to Westinghouse Air Brake Company, a corporation of Pennsylvania

Application February 27, 1951, Serial No. 212,884

11 Claims. (Cl. 246—34)

My invention relates to coded signaling systems, and particularly to an improved coded signaling system which may be applied to a conventional steady energy signaling system. More particularly, my invention relates to the application of a coded signaling system to a conventional direct current railway track circuit.

A conventional railway track circuit usually includes a source of track circuit energy, such as a battery, connected across the track rails at one end of a section or stretch of railway track, and a direct current relay connected across the rails at the other end of the stretch. Energy from the track battery flows over the rails and through the winding of the relay, so that the relay is energized and its contacts are picked up when the section is unoccupied. When a train occupies the section, the wheels and axles of the train shunt the supply of energy from the winding of the relay, so that its contacts are released. Accordingly, the usual direct current railway track circuit provides only for the detection of the occupancy of a track section by a train. In many instances, it is desirable to transmit further information including the track occupancy conditions along the rails of the track, in order to indicate various traffic conditions which may exist at some point in advance. It has previously been proposed to provide such additional channels of communication by the use of the well-known polarized track circuits, and by the use of the coded type of track circuits, in which the supply of energy to the track section from the track battery is recurrently interrupted, and the code following operation of the track relay is detected by suitable means.

However, it may at times be desirable to provide a conventional direct current track circuit, arranged so that additional information may be transmitted over the rails of the track section involved, without interfering with the normal operation of the track circuit.

Accordingly, it is an object of my invention to provide a superimposed coded signaling system which may be applied to conventional direct current track circuits, to provide an additional channel of communication over the track rails.

Another object of my invention is to provide a system of the type described in which the track rails form an indication channel which may be unidirectional or bi-directional; that is, information may be transmitted in one direction or in both directions, without interfering with the normal operation of the track circuit.

A further object of my invention is to provide a system of the type described in which the usual track battery employed for supplying energy to the track circuit may be utilized to provide the energy for the operation of the superimposed coded signal arrangement.

Other objects of my invention and features of novelty thereof will be apparent from the following description taken in connection with the accompanying drawings.

In practicing my invention, I provide, in addition to the usual track battery connected across the track rails at one end of the track stretch involved and the track

2

relay connected across the section rails at the other end of the stretch, means located at one end of the stretch, for recurrently changing the value of current flow in the track circuit, and means at the other end of the stretch responsive to such changes in the current flow, together with appropriate means for detecting the recurrent operation of the apparatus involved. In one form of my invention, I provide means including a resistance and a recurrently operated coding contact for recurrently changing the value of energy at the end of the track section where the conventional track relay is located. At the battery end of the track section, I provide a transformer having one winding connected in series with the track battery across the section rails, and having another winding connected to the winding of a code following relay. The recurrent operation of the coding contact at the track relay end of the section causes the value of energy supplied from the track battery to be recurrently changed. This recurrent change in the energy supplied through the one winding of the transformer causes impulses of energy to be induced in the other winding, which impulses are supplied to the winding of the code following relay, causing it to operate its contacts in synchronism with the operation of the coding contact at the opposite end of the section. Appropriate code detecting means are provided for detecting the recurrent operation of the contacts of the code following relay.

In a second embodiment of my invention, I provide a transformer at each end of the track circuit, one having one of its windings connected in series with the track relay across the section rails, and the other having a winding connected in series with the track battery across the section rails. The transformers are each provided with a circuit including a coding contact, a battery, and a code following track relay, and the apparatus is arranged and proportioned so that when the coding contact is recurrently operated, energy from the battery flows through one winding of the transformer, in such manner as to induce an impulse of energy in the other winding of the transformer connected with the section rails. This impulse upon reception at the opposite end of the track circuit causes a like impulse to be induced in the winding of the transformer connected at that end of the section, to thereby operate the code following relay associated with the other transformer. This arrangement is suitable for transmitting the coded information in either direction through the conventional track circuit.

I shall describe two preferred embodiments of my invention and shall then point out the novel features thereof in claims.

50 In the accompanying drawings,

Fig. 1 is a diagrammatic view of a section of railway track equipped with apparatus embodying my invention, for transmitting coded information over a conventional track circuit in one direction only.

55 Fig. 2 is a diagrammatic view of a section of railway track equipped with apparatus embodying my invention for transmitting coded information in either direction over a conventional track circuit.

Similar reference characters refer to similar parts in 60 each of the two views.

Referring to the drawings, Fig. 1 shows a section of railway track T separated from adjoining sections by the usual insulated joints 3 in the track rails 1 and 2. At the right-hand end of the section, there is provided the usual track battery TB, a limiting resistor R2, an impulse transformer TT, a code following polar stick relay CTR, a decoding transformer DT, and a code detecting relay CH. At the left-hand end of the section, there is provided the usual direct current neutral track relay TR, a pair of resistors R1 and R3, a code transmitting relay CTPR, governed by a control switch S1 and a continu-

ously-operating coding device CT. At each end of the section, energy for the operation of the apparatus other than the track circuit equipment may be furnished by a suitable source of low voltage direct current energy, such as the batteries LB, having their positive terminals designated by the reference character B and their negative terminals designated by the reference character N.

The apparatus is shown in its normal condition, with the section T unoccupied, and with the code transmitting relay CTPR deenergized. The code transmitter or coding device CT has its operating winding continuously connected across the terminals of the direct current source, and is of the type having at least one contact which is recurrently operated between its open and closed position at a predetermined rate, for example, 180 times per minute. Accordingly, it will be seen that contact *a* of coding device CT is recurrently opened and closed 180 times per minute, but no energy is supplied over the front contact *a* of coding device CT to the relay CTPR, since the switch S1 is open.

At this time also, the neutral track relay TR is energized by current flowing from the positive terminal of battery TB, through the winding 7 of transformer TT, over section rail 2, through resistor R1, through the winding of relay TR, and over section rail 1 and through resistor R2 to the negative terminal of battery TB. The components are proportioned and arranged so that the value of current which flows through the winding of relay TR at this time is sufficient to pick up the contacts of the relay. Accordingly, at this time the front contact *a* of relay TR will be closed in a control circuit, which may be used, for example, to control a signal governing the movement of trains into section T, or any other type of circuit which must respond to the occupancy of section T.

It will now be assumed that the switch S1 is closed, so that relay CTPR is recurrently energized by energy supplied from the low voltage source over the front contact *a* of the coding device CT. Accordingly, the contacts *a* and *b* of relay CTPR are recurrently picked up and released, in response to the operation of the coding contact *a* of coding device CT. When front contact *b* of relay CTPR is closed, it establishes a shunt around the resistor R1 in the circuit for supplying energy to the winding of the neutral track relay TR, and when front contact *a* of relay CTPR is closed it provides a shunt circuit across the resistor R1 and the winding of relay TR, through the resistor R3 and front contact *b*. Accordingly, it will be seen that the resistor R3 is effectively connected in multiple with the winding on track relay TR across the section rails 1 and 2 at this time. The value of resistor R3 is chosen so that the current which flows through the winding of track relay TR at this time will not be reduced below the point where the contacts of the relay will release, since, as is well-known in the art, the release value of current for the track relay TR is substantially less than the pick up value. Accordingly, while the contacts *a* and *b* of code transmitting relay CTPR are recurrently opened and closed, the contacts of track relay TR will remain in their picked up position, since the current through the winding is not reduced below the drop away for the particular relay employed.

However, the change in current produced by the alternate shunting of the resistor R3 across the winding of relay TR and the short circuiting of resistor R1 produces a change in the value of current which flows from the track battery TB. The change of current flowing in the winding 7 of transformer TT causes energy to be induced in the second winding 9 of transformer TT, the polarity of the energy being alternately reversed in accordance with the increase or the decrease in the value of current flowing through the winding 7. Thus, it will be seen that the recurrent changes in the current flowing through the winding 7 of transformer TT as the result of the shunting operation of the contacts of relay CTPR at the opposite end of the track circuit will cause

impulses of energy of alternate opposite polarity to be induced in the second winding 9 of the transformer TT, which impulses are supplied to the winding of the polar stick code following relay CTR. Relay CTR is of the type in which the contacts remain in the position to which they were last operated, until the relay is energized with energy of opposite polarity, whereupon the contacts will move to corresponding position, and remain there when the relay is deenergized. At this time, therefore, it will be seen that the winding of relay CTR is supplied with pulses of energy of alternate opposite polarity from the winding 9 of transformer TT, and as a result, the contacts of relay CTR are recurrently operated between their normal or left-hand position, and their reversed or right-hand position. The code following operation of relay CTR may be detected by any of the means well-known in the art, and as here shown a decoding transformer and a slow release, slow pick up relay are employed to detect the code following operation of the relay contacts. The two halves of the primary winding 13 of the decoding transformer DT are alternately supplied with energy from the direct current source over the contact *a* of relay CTR, and the energy induced in the secondary winding 15 is mechanically rectified by the action of contact *b* of relay CTR and is supplied to the winding of the code detecting relay CH. Relay CH is slightly slow in releasing its contacts, so that it remains picked up during the intervals in which no energy is supplied to its winding, that is, while the contacts of relay CTR are transferring from one position to the other. Such a code detecting arrangement is more fully described in Letters Patent of the United States No. 2,237,788, issued to Frank H. Nicholson et al., and a detailed explanation of the operation of the equipment is deemed unnecessary. The contacts of relay CH may be used to control any suitable circuits, such as for example, the control of wayside signals for the section T, the control of approach indications at an interlocking plant or other control circuits.

If it is now assumed that a train enters and occupies section T, it will be seen that the wheels and axles of the train will shunt the supply of energy from the winding of the neutral track relay TR, so that relay TR will release its contacts and they will remain released as long as the track section T is occupied. Moreover, the train shunt presents a relatively low and substantially constant resistance to the flow of energy from the battery TB, so that the rate of change of current flowing in the winding 7 of transformer TT, if any, during the time that the section T is occupied, will be insufficient to cause the operation of relay CTR. Accordingly, the relay CTR will stop operating its contacts, and after a short time interval, the code detecting relay CH will release its contacts, thereby opening or closing any circuits governed by this relay.

When the train vacates section T, the supply of energy from battery TB over the section rails 1 and 2 to the winding of track relay TR is again resumed, so that relay TR picks up its contact *a* at least during the first time period in which contacts *a* and *b* of relay CTPR are released, and thereafter remains picked up, thereby opening or closing the circuits governed by this contact. Additionally, the resistor R3 is recurrently shunted across the winding of relay TR, so that the value of energy flowing in the transformer TT is changed, thereby supplying impulses of induced energy to the winding of the code following relay CTR, so that its contacts again recurrently operate between their normal or reversed position. With the contacts *a* and *b* of relay CTR recurrently operating, energy is supplied over the contact *a* to the primary winding 13 of the decoding transformer DT, and the energy induced in the secondary winding 15 of the transformer DT is rectified by the contact *b* of relay CTR and supplied to the winding of the code detecting relay CH, so that the contact of relay CH picks up. The circuits controlled over contact *a* of the code detecting relay CH

are accordingly opened or closed, to indicate the absence of a train from the section T, and the transmission of additional communication as a result of the switch S1 being closed.

It will be noted that if the relay CTPR is deenergized by the opening of the switch S1 during the time a train occupies the section T, the change in the flow of energy from the battery TB through the primary winding 7 of transformer TT when the train vacates the section may be sufficient to induce an impulse of energy in the secondary winding of the transformer, which may operate the contacts of relay CTR from one position or the other, according as the contacts were last energized in their normal or reverse position. This so-called "single stroke operation" of the contact of the code following relay CTR will not result in the picking up of the code detecting relay CH, since this relay is constructed and arranged not only to be slow in releasing its contacts, but additionally to be slow in picking up its contacts, so that energy supplied to its winding as a result of the single operation of the contacts of relay CTR is insufficient to cause the relay to pick up its contact *a*. Accordingly, a single change of the rate of current flow to the transformer TT will not cause erroneous operation of the equipment.

It will be seen from the foregoing, that a track circuit arranged in accordance with my invention provides means for supplying additional communication or information over a conventional track circuit, which requires a minimum amount of apparatus, is reliable, and utilizes the conventional track battery as a source of energy for providing the extra communication channel over the track. It will also be seen that this additional channel provided by the coding of track circuit energy is responsive to the presence of the train in the section. Accordingly, it will be obvious to those skilled in the art that the contacts of the conventional track relay such as the relay TR may be used to govern the usual wayside signal equipment, while the additional channel furnished by the coding apparatus may be used for governing circuits such as highway crossing approach control circuits, approach indication circuits, and other circuit arrangements of this type. Moreover, it will be seen that the arrangement is not limited to use with track circuits, but may be used with circuits in which the conductors are line wires, instead of the rails of a track section. Accordingly, a neutral type line circuit may be substituted for the track rails 1 and 2, and by providing suitable shunting or circuit opening means for the line circuit, the same effects will be secured as described in connection with Fig. 1.

Referring now to Fig. 2, there is shown a section of railway track T having track rails 1 and 2, and insulated from the adjacent sections by insulated joints 3. This track section is provided with a conventional direct current track circuit including the track battery TB and the track relay TR connected across the rails at the opposite ends of the track section. Additionally, apparatus is provided for superimposing impulses upon the direct current track circuit energy, so that an additional channel of communication is afforded, which may be operated in either direction, as will be subsequently described. This additional apparatus comprises a transformer such as the transformers LTT and RTT connected in series with the track leads at each end of the section, a code transmitting relay such as the relays LCTPR and RCTPR, which are each governed by a code transmitter and a control switch, a code following relay such as relays LCTR and RCTR, and a source of code energy such as the batteries LCTB and RCTB, and code detecting equipment for detecting the recurrent operation of the code following relays, such as the transformers RDT and LDT, with their associated code detecting relays RCH and LCH. As in Fig. 1, the energy for the operation of the apparatus other than that associated directly with the track circuit is furnished at each end of the track circuit by a

suitable source of low voltage direct current energy, such as the batteries LB, each having a positive terminal designated by the reference character B and a negative terminal designated by the reference character N, respectively.

The arrangement of apparatus shown in Fig. 2 may be more clearly understood by describing the operation of the apparatus under various conditions. It will first be assumed that the apparatus is in its normal condition, as shown, with no train occupying the section T. At this time, the neutral track relay TR is supplied with energy from the track battery TB, by a circuit which may be traced from the positive terminal of the battery TB, through the winding 19 of transformer LTT, over section rail 2, through the winding 21 of transformer RTT, through the winding of the track relay TR, over section rail 1, and through the resistor R2 to the negative terminal of battery TB. Accordingly, the relay TR will be energized and its contact *a* will be picked up to thereby control any circuits which may be governed thereby.

The windings of the code transmitters LCT and RCT are continuously connected to the source of low voltage energy, and accordingly the contacts are recurrently opened and closed at a predetermined rate, for example, 180 times per minute. However, with the control switches LS and RS open, the code transmitting relays LCTPR and RCTPR will be deenergized.

It will now be assumed that it is desired to transmit coded energy over the track section T from the left-hand end of the section to the right-hand end of the section. Accordingly, the contact of switch LS is closed, so that coded energy is supplied by an obvious circuit to the winding of relay LCTPR. Accordingly, 180 times per minute the contact *a* of relay LCTPR will operate between its front and back contacts. When the contact *a* of relay LCTPR picks up, it establishes a circuit for supplying energy from the battery LCTB to the winding 23 of transformer RTT. When the contact *a* of relay LCTPR releases, it disconnects the battery LCTB from the winding 23 of transformer RTT and connects the winding of the code following relay RCTR to the winding 23 of the transformer. The supply of impulses of energy from the battery LCTB to the winding 23 of transformer RTT causes impulses of energy to be induced in the winding 21 of the transformer RTT. The condenser TQ, connected across the winding of relay TR, affords a low impedance path for these impulses to be supplied across the rails 1 and 2 of section T. These impulses are accordingly supplied over the rails 1 and 2 of section T to the right-hand end of the section, and flow through the winding 19 of transformer LTT, the battery TB and the resistor R2. The parts are proportioned and arranged so that the pulses of energy thus induced in the winding 25 of transformer LTT are sufficient to cause operation of relay LCTR, which has its winding connected to the winding 25 of transformer LTT over the back contact *a* of relay RCTPR.

The impulses of energy supplied from the winding 25 of the transformer LTT, over back contact *a* of relay RCTPR to the winding of the code following relay LCTR are of relative opposite polarity, and as a result, the contacts of relay LCTR are recurrently operated between their normal and reverse positions, in step with the supply of energy from the battery LCTB over the front contact *a* of relay LCTPR to the winding 23 of transformer RTT. The recurrent operation of the contacts *a* and *b* of relay LCTR is detected by means of the conventional code detecting relay LCH, in conjunction with the decoding transformer LDT. When the contacts of relay LCTR are operating, impulses of unidirectional energy are supplied from the transformer LDT to the winding of relay LCH, so that the contact *a* of relay LCH is picked up to thereby open or close the control circuits governed by this relay.

From the foregoing, it will be seen that at this time with the track section T unoccupied, the neutral track relay TR is energized by the energy supplied over the track rails from the conventional track relay TB, and there is superimposed upon this energy impulses of low frequency energy supplied from the transformer RTT, which pulses are supplied to the transformer LTT to operate the code following relay LCTR.

If it is desired to transmit information over the section T from the right-hand end to the left-hand end of the section, and assuming that the apparatus is in its normal condition as shown in the drawing, the switch RS may be closed at the right-hand end of the section, to thereby recurrently energize the code transmitting relay RCTPR, so that it recurrently connects the battery RCTB to the winding 25 of the transformer LTT. The impulses of energy induced in the winding 19 of transformer LTT are superimposed upon the direct current energy supplied from battery TB, and flow through the winding 21 of transformer RTT at the left-hand end of the section, and through the condenser TQ which by-passes the winding of the conventional track relay TR. The impulses thereby induced in the winding 23 of transformer RTT are supplied to the winding of relay RCTR over back contact *a* of the code transmitting relay LCTPR, which relay is deenergized at this time by the opening of the switch LS, so that relay RCTR operates its contacts in response to the recurrent supply of energy to the transformer LTT at the other end of the section. As in the case of relay LCTR, the code following operation of relay RCTR is detected by the conventional arrangement of the code detecting transformer RDT and code detecting relay RCH, so that when relay RCTR is following code, the relay RCH will be energized and its contact *a* will open or close the control circuits governed by this relay.

From the foregoing, it will be seen that the track circuit arrangement shown in Fig. 2 and embodying my invention is arranged so that an additional communication channel is provided over a conventional direct current track circuit, in which the information may be transmitted from either end of the section to the other end of the section. As pointed out in connection with Fig. 1, the conventional track relay TR may govern wayside signals for controlling the movements of trains into the section T, while the code apparatus may control auxiliary circuits, such as highway crossing approach control circuits, approach lighting circuits, etc.

Additionally, as was pointed out in connection with Fig. 1, the entrance of a train into section T will cause the track circuit to be shunted, so that not only is the conventional track relay TR released, but the supply of code impulses, if they are being transmitted at this time, is cut off, so that the code detecting relay would at the appropriate end of the section become deenergized. When the train enters or leaves the track section, particularly at the right-hand end where the track battery TB is located, it will be seen that a change in the value of current flowing in the winding 19 of transformer LTT will take place. However, the impulse induced in the winding 25 of transformer LTT by this action will only cause the code following relay to move its contacts from one position to the other, and the code detecting apparatus is arranged and constructed so that the code detecting relay, such as relay LCH, which is not only slow in releasing its contacts but also slow in picking them up, will not pick up its contacts from the so-called "single stroke operation."

From the above description of two forms of railway signaling systems embodying my invention, it will be apparent that I have provided a simple and reliable means of superimposing an additional communication channel upon a steady energy direct current railway track circuit, and although I have herein shown and

described only two forms of superimposed coded signaling systems embodying my invention, it is to be understood that various changes and modifications may be made therein within the scope of the appended claims without departing from the spirit and scope of my invention.

Having thus described my invention, what I claim is:

1. In combination, a pair of conductors, a source of direct current energy connected across said conductors at one end thereof and an electro-responsive device connected across said conductors at the other end thereof, said electro-responsive device being responsive to a predetermined minimum value of energy supplied thereto over said conductors, means located at one end of said pair of conductors for recurrently changing the value of energy supplied from said source to said electro-responsive device between a first value which is greater than said predetermined minimum value and a second value which is greater than said first value, and means located at the other end of said pair of conductors responsive to changes of energy supplied from said source to said conductors, when said changes are recurrent and are at least as great as the difference between said first and said second values.
2. In combination, a pair of conductors, a source of direct current energy connected across said conductors at one end thereof, a relay having an operating winding connected across said conductors at the other end thereof, said relay having contacts which are picked up when a predetermined minimum value of energy is supplied to said winding over said conductors, means connected at one end of said conductors for recurrently changing the value of energy supplied from said source to said winding between a first value which is greater than said predetermined value and a second value which is greater than said first value, and means connected at the other end of said pair of conductors responsive to recurrent changes in the value of energy supplied from said source to said conductor, said changes being at least as great as the difference between said first and said second values.
3. In combination, a section of railway track, a track battery connected across the rails of said section at one end thereof, a track relay having a winding connected across the rails of said section at the other end thereof, said track relay having a contact which is picked up only when energy of a predetermined value is supplied to the relay winding over the rails of said section from said track battery, a first means for at times recurrently changing the value of energy supplied to said relay winding between a first value which is greater than said predetermined value and a second value which is greater than said first value, and second means for detecting the recurrent changes in value of the energy supplied to said winding, said first and said second means being connected to said track sections at opposite ends thereof.
4. In combination, a section of railway track, a track battery connected across the rails of said section at one end thereof, a track relay having a winding connected across the rails of said section at the other end thereof, said track relay having a contact which is picked up only when energy of a predetermined value is supplied to the relay winding over the rails of said section from said track battery, a first means for at times recurrently changing the value of energy supplied to said relay winding between a first value which is greater than said predetermined value and a second value which is greater than said first value, and second means for detecting the recurrent changes in the value of the energy supplied to said relay winding, comprising a transformer having a first winding interposed in the connection between said battery and said relay winding including the rails of said section, a code following relay having a winding connected to a second winding of said transformer, and code detecting means for detecting the recurrent operation of said code following relay, said first and said second means being connected to said track circuit at opposite ends thereof.

5. In combination, a section of railway track, a track battery connected across the rails of said section at one end thereof, a track relay having a winding connected across the rails of said section at the other end thereof, said track relay having a contact which is picked up only when energy of a predetermined value is supplied to the relay winding over the rails of said section from said track battery, a recurrently operated contact, a resistor, means including said recurrently operated contact for at times shunting said resistor across said track relay winding, said resistor being selected so that the value of energy supplied to the winding of said track relay when said resistor is shunted across the winding is at least as great as said predetermined value, a transformer having a first and a second winding, said first winding being connected in series with said track battery across the rails of the section, a code following relay having a winding connected across said second winding of said transformer, and means for detecting the code following operation of said code following relay, the parts being proportioned so that the energy induced in the second winding of said transformer by the current changes in the first winding of said transformer when said track relay winding is recurrently shunted by said resistor is sufficient to operate the code following relay.

6. In combination, a section of railway track, a track battery connected across the rails of said section at one end thereof, a track relay having a winding connected across the rails of said section at the other end thereof, said track relay having a contact which is picked up only when energy of a predetermined value is supplied to the relay winding over the rails of said section from said track battery, coding means located at each end of said section for recurrently changing the value of energy supplied to said relay winding between a first value which is greater than said predetermined value and a second value which is greater than said first value, selecting means for energizing said coding means at one end or the other end of said section, and means located at each end of said section for detecting recurrent changes in the energy supplied to said section between said first value and said second value.

7. In combination, a section of railway track, a track battery connected across the rails of said section at one end thereof, a track relay having a winding connected across the rails of said section at the other end thereof, said track relay having a contact which is picked up only when energy of a predetermined value is supplied to the relay winding over the rails of said section from said track battery, coding means located at each end of said section for recurrently changing the value of energy supplied to said relay winding between a first value which is greater than said predetermined value and a second value which is greater than said first value, selecting means for energizing said coding means at one end or the other end of said section, means located at each end of said section for detecting recurrent changes in the energy supplied to said section, comprising a transformer having a first and a second winding, said first winding being connected to the track rails of the section so that the energy flowing in said track rails also flows through said first winding, a code following relay having a winding connected to said second winding of the transformer, and code detecting means for detecting the recurrent operation of said code following relay, the parts being proportioned so that the code following relay will operate in response to the changes of energy in said section between said first and said second values.

8. In combination, a section of railway track, a track battery connected across the rails of said section at one end thereof, a track relay having a winding connected across the rails of said section at the other end thereof, said track relay having a contact which is picked up only when energy of a predetermined value is supplied to the relay winding over the rails of said section from said

track battery, a first code following relay, a first transformer having a first winding connected in series with said track relay winding and having a second winding connected at times to a winding of said first code following relay and adapted to be recurrently connected at other times to a first source of direct current energy, a second code following relay, a second transformer having a first winding connected in series with said track battery and having a second winding connected at times to a winding of said second code following relay, and adapted to be recurrently connected at other times to a second source of direct current energy, code detecting means associated with each of said code following relays and governed thereby to detect the code following operation of the associated relay, selecting means for selectively recurrently connecting one or the other of said second windings of said transformers to the associated source of direct current energy, and control circuits governed by the contact of said track relay and by said code detecting means.

9. In combination, a pair of conductors extending between two spaced points, a source of direct current, a winding, said source and said winding connected in series across said conductors at a first one of said points, a direct current electro-responsive device connected across said conductors at a second one of said points and effectively energized in response to a predetermined minimum value of direct current supplied by said source to said conductors, coding means having a contact recurrently operated between two positions, means including impedance elements and said contact connected across said conductors at said second point for recurrently changing the value of the direct current flowing from said source to said winding through said conductors, said direct current being changed between a first value which is at least as great as said predetermined value and a second value greater than said first value, and another electro-responsive device coupled to said winding and responsive to changes of direct current flowing through said winding when said changes are recurrent and are at least as great as the difference between said first and said second values.

10. In combination, a track section provided with a direct current track circuit including a direct current source connected across the rails at one end of the section and a direct current relay connected across the rails at the other end of the section, said relay being effectively energized in response to a predetermined minimum value of current supplied by said source to said track circuit, a winding interposed in the connection of said source to said track circuit, coding means having a contact recurrently operated between two positions, means including said contact and impedance elements connected across the rails at said other end of the section for recurrently changing the value of the direct current flowing from said source through said winding to the rails of said section, said change being between a first value which is at least as great as said predetermined value and a second value which is greater than said first value, and an electro-responsive means coupled to said winding and responsive to changes of direct current flowing through said winding when said changes are recurrent and are at least as great as the difference between said first and said second values.

11. In combination, a pair of conductors, a source of direct current energy connected across said conductors at one end thereof, an electro-responsive device connected across said conductors at the other end thereof, said electro-responsive device being responsive to a predetermined minimum value of energy supplied thereto over said conductors, means located at one end of said pair of conductors for recurrently changing the value of energy supplied from said source to said electro-responsive device between a first value which is greater than said predetermined minimum value and a second value which is greater than said first value, and means located at the other end of said pair of conductors responsive to changes

of energy supplied from said source to said conductors, when said changes are recurrent and are at least as great as the difference between said first and said second values, said last named means comprising a transformer having a first and a second winding, said first winding being connected in series with one of said pair of conductors, a code following relay having an operating winding connected to the second winding of said transformer, and having contacts which are operated recurrently in response to said recurrent changes, and code detecting means responsive to recurrent operation of the contacts of said code following relay.
